M. NADEAU AND A. BOUVIER.
CHECK FOR LOOMS.
APPLICATION FILED JULY 14, 1919.

1,315,388.

Patented Sept. 9, 1919.

UNITED STATES PATENT OFFICE.

MICHEL NADEAU, OF AUBURN, AND ADOLPHE BOUVIER, OF LEWISTON, MAINE.

CHECK FOR LOOMS.

1,315,388.

Specification of Letters Patent. Patented Sept. 9, 1919.

Application filed July 14, 1918. Serial No. 310,553.

To all whom it may concern:

Be it known that we, MICHEL NADEAU and ADOLPHE BOUVIER, citizens of the United States, residing at Auburn and Lewiston, respectively, in the county of Androscoggin, State of Maine, have invented a new and useful Check for Looms, of which the following is a specification.

This invention relates to checks for looms one of its objects being to provide a simple and compact device constituting an efficient check for the shuttle of a box loom and which can be applied readily to the back of the lay and under the shuttle box.

Another object is to provide a device of this character which can be used on any standard form of single box loom.

With the foregoing and other objects in view, which will appear as the description proceeds, the invention consists of certain novel details of construction and combinations of parts which will be hereinafter more fully described and pointed out in the claims, it being understood that various changes may be made in the construction and arrangement of the parts without departing from the spirit or sacrificing any of the advantages of the invention as set forth in the claims.

In the accompanying drawings the preferred form of the invention has been shown.

In said drawings—

Figure 1 is an elevation of the device in position.

Fig. 2 is a horizontal section through the check on the line 2—2, Fig. 3.

Fig. 3 is a central vertical transverse section through the device, on the line 3—3, Fig. 2.

Fig. 4 is a plan view of the friction shoe. Fig. 5 is a side view thereof.

Referring to the figures by character of reference, A designates a portion of the lay of a loom and B designates a shuttle box. The check constituting the present invention is adapted to be secured to the back of the lay and under the shuttle box and includes an attaching plate 1 having a slot 2 for the reception of an attaching bolt. Lugs

3 extend from the plate 1 and are designed to extend under the lay, thus to hold the plate against rotation about the bolt in the slot 2. Extending along the lower edge of the plate 1 at right angles thereto and under the lay is a flange 4 provided in its

free longitudinal edge with spaced dovetail recesses 5 adapted to receive the dovetailed lower ends of guide fingers 6 extending downwardly from a top plate 7 on which are formed reinforcing ribs or webs 8. The fingers are adapted to be inserted downwardly into the recesses 5 after which the top plate 7 and webs 8 are secured to the plate 1 by screws 9 or the like inserted through the plate. The plate 1 is preferably formed with upper and lower openings 10 separated by a bar 11 and a lug 12 extends laterally from the central portion of this bar and under the top plate 7.

Extending through the center portion of the flange 4 is an adjusting screw 13 preferably provided with a lock nut 14 and bearing downwardly upon this screw is a bowed spring 15 the ends of which are slightly downturned and which spring forms a friction shoe. The sides of the spring are extended laterally to form shoulders 16 which project between the fingers 6 and under the bar 11, thereby to hold the spring against longitudinal displacement.

A slide 17 is mounted on the ends of the spring shoe 15 and is pressed thereby against the lower face of the top plate 7. This slide has a recess 18 in one side into which the lug 12 projects and the walls of the recess are covered with leather or other cushioning material as shown at 19. Oppositely extended U-shaped arms project from the ends of the slide, as shown at 20 and the ends of the arms lap and interfit, as at 21, and are held together by a bolt 22.

A picker arm is adapted to work within the loop formed by the arms 20 and when it strikes either end portion of the loop it will shift the slide 17 longitudinally until one end of the recess 18 comes against the lug 12. The cushioning strip 19 reduces the pounding and the spring shoe 15 acts to retard the movement of the slide and, consequently, the picker arm.

By employing the lapping connected arms 20 the device can be applied readily to the picker arm and lay. The screw 13 allows the tension of the spring shoe to be adjusted as desired.

What is claimed is:—

1. A check attachment for single box looms, including an attaching plate, a flange thereon, a lug upon the plate and overhanging the flange, a top plate detachably fastened to the attaching plate, guide fingers

depending from the top plate and connected to the flange, a spring shoe adjustably supported above the flange, a slide mounted on the shoe and frictionally engaging the top plate, said slide having a recess into which the lug extends, and a loop carried by the slide for the reception of a picker arm.

5. 2. A check attachment for single box looms including an attaching plate having a flange, a lug on the plate, a top plate detachably connected to the attaching plate and flange, an adjustably supported spring shoe, a slide on the shoe and frictionally

engaging the top plate, said slide having a recess for the reception of the lug, a cushion 15 in the recess, opposed curved arms on the slide and connected together to form a picker-arm receiving loop.

In testimony that we claim the foregoing as our own, we have hereto affixed our signatures in the presence of two witnesses.
